UNITED STATES PATENT OFFICE.

WALTON D. WOOLLEY, OF CHICAGO, ILLINOIS, ASSIGNOR TO KILLARK ELECTRIC MANUFACTURING COMPANY, OF ST. LOUIS, MISSOURI, A CORPORATION OF MISSOURI.

FUSE-PLUG.

1,308,518.

Specification of Letters Patent.

Patented July 1, 1919.

Application filed July 17, 1917. Serial No. 181,048.

To all whom it may concern:

Be it known that I, WALTON D. WOOLLEY, a citizen of the United States, residing at the city of Chicago, county of Cook, State of Illinois, have invented a certain new and useful Improvement in Fuse-Plugs, of which the following is a specification, reference being had to the accompanying drawing, forming a part thereof.

10 This invention relates generally to electric safety fuses or cut-outs and, more especially, to a certain new and useful improvement in that type of safety fuses or cut-outs commonly known as fuse-plugs.

15 Fuses of the type stated comprise a fusible element which, when the fuse or plug is inserted or placed in an electric circuit, is adapted and designed to carry or conduct the normal current of the circuit and to

20 blow or fuse on an overload or abnormal current, the circuit being thereby opened and the translating devices or the like in the circuit consequently protected from injury or damage from such overload or excess of

25 current. So far as I am aware, fuse-plugs have heretofore been usually so constructed that, on a burning or blowing out of the fusible element, the plug, although, except for its fusible element, substantially unaffected by such occurrence, was discarded as useless by the user.

The principal object of my present invention is to provide an efficient fuse-plug of few readily assembled members so constructed and cooperating that the plug may be easily taken apart and the fusible element inexpensively renewed with convenience and facility, repeated use of the other and generally more costly members or parts of the plug being thereby obtained and a consequent saving of expense and economy of material effected.

With the above and other objects in view, my present invention resides in certain novel features of form, construction, arrangement, and combination of parts, all as hereinafter described and afterward pointed out in the claims.

In the accompanying drawing,

50 Figure 1 is a sectional view of a fuse-plug embodying my invention in preferred form;

55 Fig. 2 is a plan view of the same;

Fig. 3 is an elevational view, partly in section, of the casing or outer member of the

55 plug;

Fig. 4 is a similar view of the body or inner member of the plug;

Fig. 5 is an elevational view of the plug;

Fig. 6 is a perspective view of one of the renewable fusible elements or strips of the

60 plug;

Fig. 7 is a sectional view of a slightly modified form of the outer or casing-member of the plug;

Fig. 8 is a sectional view of a slightly 65 modified fuse-plug embodying my invention; and

Fig. 9 is a perspective view of the renewable fusible element or strip of the modified 70 fuse-plug of Fig. 8.

As illustrated in the said drawing, in which like reference characters refer to like parts throughout the several views, my present fuse-plug comprises, generally speaking, substantially but three readily separable 75 members or parts, namely, a body-member, a fusible element, and a casing, the casing forming one of the terminals, and being also the socket-engaging member, of the plug.

The fusible element is in the form preferably of a thin strip or ribbon of suitable fusible metal or alloy adapted and designed to conduct or carry the normal current of the circuit in which the particular plug may be inserted, this strip having a somewhat 80 elongated end-portion 1 and an intermediate portion 2 of reduced cross-section to blow or fuse on approximately a predetermined overload or excess of current beyond the normal current of the circuit. The opposite 85 end-portion of the strip, as hereinafter more fully appears, extends into or through an aperture in the body-member to form, directly or indirectly, the end or center contact or terminal of the plug and, in the preferred form of the plug, is reinforced by and includes a fixed section of somewhat 90 heavier metal bent intermediate its ends to provide a contact-piece 3, the legs 3^a of such section extending for the greater part of 100 their length flatwise upon opposite sides of, and being soldered or otherwise electrically connected to, said end-portion of the strip. The tips or ends 3^b of the legs 3^a, being unattached to the strip, provide holding-shoulders for the strip, which shoulders normally 105 oppositely project yieldingly laterally away from the strip, as seen in Fig. 6.

4 indicates the body-member of the plug, which is preferably, as shown, a substan-

110

tially cup-shaped section of porcelain, fiber, or other suitable insulation material molded or otherwise formed into the desired shape, member 4 having an interior chamber or cavity 5 and being for the greater part of its length spirally corrugated or threaded, as at 6, upon its outer surface or periphery. Approximately centrally through its end wall, member 4 is provided with an aperture or slot 7 to accommodate the reinforced end-portion of the fuse-strip. At its rim, member 4 is cut away or otherwise formed to provide a second aperture 8 for the opposite end-portion 1 of the fuse-strip.

15 The casing or outer member of the plug is substantially of unitary construction and comprises a ring or annulus 9 of suitable insulation material, which is preferably cut away, as at 10, to provide a seat for a mica disk 11, the annulus or ring 9 with its disk 10 forming a so-called lid adapted, when the parts of the plug are assembled, to close the open end of chamber 5 of member 4 and provide a window 20 through which the condition of the fuse-strip within member 4 may be observed. Permanently holding mica-disk 11 to its seat, is a metallic tubular member or shell 12, one, or the upper, end of which is disposed within the aperture of, and crimped or otherwise rigidly fixed to, ring 9, as seen particularly in Figs. 1 and 3. Shell 12 is of a length and diameter to correspond approximately with the length and exterior diameter of member 4 and is correspondingly corrugated or threaded, as at 13, the casing being adapted not only to removably fit upon and embrace, and to separably engage threadedly at its shell 12 with, body-member 4, as illustrated in Figs. 1 and 5, but to also operatively engage threadedly with the usual plug-socket (not shown) included in the circuit to be protected.

In assembling the parts of the plug, a 45 fuse-strip is drawn at its end-portion 1 endwise through aperture 7 to seat contact-piece 3 upon the outer face of the end-wall of member 4 and to dispose its intermediate or reduced portion 2 within chamber or cavity 5 of member 4. In such operation, the tips or ends 3^b of contact-piece 3 are pinched flatwise upon the strip to pass with the strip through the aperture 7. The contact-piece 3 being seated upon, and intermediate strip-portion 2 being disposed within, member 4 as described, the tips 3^b assume their normal lateral position relatively to the strip and thereby engage upon the inner face of the end-wall of member 4 and 50 removably hold the contact-piece 3 operatively to its seat, as seen in Fig. 1. End-portion 1 of the strip is now passed outwardly through opposite or side-wall aperture 8 and then bent downwardly to extend 55 lengthwise along the threaded face of mem-

ber 4, laterally projecting shoulders 14 on the strip being adapted to engage the wall of member 4 at opposite sides of said outlet aperture 8 to properly position and hold the fuse-strip relatively to body-member 4. A 70 casing is then threaded upon the body-member and the thin bent end-portion 1 of the strip tightly wedged, in such operation, between body-member 4 and shell 12. The fuse-strip is thereby firmly held in operative 75 position in the plug and in electrical contact or engagement with shell 12, shell 12 forming the side contact or terminal of the plug. It may be here stated that the shoulders 14 also hold the strip from being further drawn through the aperture 8 during the threading of the casing upon body-member 4. The plug may now be employed as an ordinary or standard plug and threaded into the usual plug-socket, the lid of the 80 casing providing means for the convenient seating and unseating of the plug and the shell of the casing providing means for the mechanical and electrical engagement of the plug with the socket. On a blowing 85 or fusing of the fuse-strip of the plug, the plug may be conveniently engaged at its ring 9 and unscrewed from such socket, the casing then unscrewed from the body-member of the plug, an annular series of 90 recesses 15 on the end wall of member 4 providing finger-grips to facilitate separation of casing and body-member, the parts of the blown strip removed, and a new strip substituted or inserted and the parts again 95 operatively assembled, as described, when the plug is again ready for use. While the spring tips 3^a sufficiently engage with body-member 4 to hold contact-piece 3 to its seat on a blowing of the strip, the contact-piece 100 3 of a blown strip may be conveniently removed or pried from its seat for the substitution of a second strip by positive outward pressure or pull exerted thereupon by 105 means of any suitable tool (not shown). If 110 desired, contact-piece 3 of the fuse-strip may have stamped thereupon as illustrated any suitable mark or number to indicate the normal ampere carrying capacity of the strip. Side-wall aperture 8, as well as also 115 preferably an additional aperture 16 provided in the rim of member 4, serve as vent openings for the escape from the plug of the gases generated on a blowing or fusing of a 120 fuse strip.

In Fig. 7, I have shown a slightly modified form of casing-member for the plug. In this form, the mica disk 11' and the upper end of shell 12' are embedded in the ring or annulus 9' during the manufacture 125 of ring 9', the casing so formed being substantially an integral structure.

In Figs. 8 and 9, I show a slightly modified fuse-plug and its fusible element or strip. In this form of plug, the body-mem- 130

ber and casing are substantially similar in all respects to the body-member and casing of the preferred form of plug shown in Figs. 3 and 4 and are accordingly identified by 5 the same reference characters. The fusible-element or strip, however, has, as shown, elongated end-portions 1' and 17, an intermediate or reduced portion 2', outwardly projecting shoulders 14' similar in form and 10 function to shoulders 14 of the preferred form of strip, and a second pair of outwardly projecting lateral shoulders 18 in lieu of the shoulders 3^b of the preferred form of strip. In assembling this form of my fuse- 15 plug, the end-portion 17 of the strip is projected outwardly of body-member 4 through aperture 7 and shoulders 18 engaged with the inner face of end wall of member 4. The outwardly projecting part of end-portion 17 of the fuse-strip is then folded or 20 bent upon itself, as illustrated in Fig. 8, beneath the end wall of the body-member 4, to directly provide the center terminal or end-contact of the plug. Otherwise the 25 assembling of this form of plug is approximately similar to the assembling of the preferred form previously described, the shoulders 18 removably holding the bent end-portion 17 of the strip to its seat on a blowing 30 of the strip. If desired, end-portion 17 of the fuse-strip may similarly have stamped thereupon, as shown, any suitable mark or number to indicate the normal ampere carrying capacity of the strip.

35 I am aware that minor changes in the form, construction, arrangement, and combination of the several parts of my new fuse-plug may be made and substituted for those herein shown and described without 40 departing from the nature and principle of my invention.

Having thus described my invention, what I claim and desire to secure by Letters Patent is:

45 1. A fuse-plug including, in combination, a cup-shaped body-member, a renewable fuse-strip disposed with an intermediate portion within the chamber of the body-member and an end-portion projecting exteriorly thereof, and a removable unitary casing comprising a lid for closing the open 50 end of the chamber of the body-member and a terminal-forming shell of approximately uniform diameter throughout engaging separately with the body-member and the projecting end-portion of the strip.

55 2. A fuse-plug including, in combination, an exteriorly threaded cup-shaped body-member, a renewable fuse-strip having an intermediate portion disposed within the chamber of the body-member and an end-portion projecting exteriorly thereof, and a unitary casing removably threaded upon the body-member and comprising a lid for 60 closing the open end of the chamber of the

body-member and a threaded terminal-forming shell separably engaging the projecting end-portion of the strip.

3. A fuse-plug including, in combination, an exteriorly threaded cup-shaped body-member, a renewable fuse-strip disposed with an intermediate portion within the chamber of the body-member and an end-portion projecting exteriorly thereof, the other end-portion of the strip being adapted 70 for electrical contact with the center contact of a plug-socket, and a unitary casing removably threaded upon the body-member and comprising a lid for closing the open end of the chamber of the body-member 80 and a terminal-forming shell separably engaging the projecting end-portion of the strip.

4. A fuse-plug including, in combination, an exteriorly threaded cup-shaped body-member, a renewable fuse-strip disposed with an intermediate portion within the chamber of the body-member and an end-portion projecting exteriorly thereof, the other end-portion of the strip being adapted 85 for electrical contact with the center contact of a plug-socket, and a unitary casing removably threaded upon the body-member and comprising a lid for closing the open end of the chamber of the body-member 90 and a terminal-forming shell separably engaging the projecting end-portion of the strip, the projecting end-portion of the strip being wedged between the shell and body-member in the threading of the casing upon 95 the body-member.

5. In a fuse-plug, the combination with an exteriorly threaded chambered body-member having an aperture in its wall, of a fuse-strip having an intermediate portion 105 disposed within the chamber of the body-member and an end-portion projecting exteriorly thereof through said aperture, a casing-shell threaded upon the body-member, the projecting end-portion of the strip 110 being wedged between the shell and body-member in the threading of the shell upon the body-member, and means on the strip for engagement with the body-member to hold the strip from endwise movement 115 through said aperture during the threading of the shell upon the body-member.

6. A renewable fuse-plug including a chambered body-member having an aperture in its wall, in combination with a separable fuse-strip having an intermediate portion disposed within the chamber of the body-member and a reinforced shouldered contact-forming end-portion extending through said aperture, the shoulders of said 120 end-portion being also disposed within the chamber of the body-member and engaging with the inner face of the wall thereof for normally holding the strip from endwise movement through said aperture. 125 130

7. A renewable fuse-plug strip having a reinforcing terminal-forming section fixed upon an end-portion thereof, said section including portions disposed flatwise upon opposite sides of the strip, the ends of said portions forming body-member engaging shoulders for the strip.
8. A renewable fuse-plug including a separable fuse-strip, in combination with an externally threaded cup-shaped body-member, and a unitary casing fitting removably upon the body-member and comprising an insulation window closing the open end of the chamber of the body-member and a threaded terminal-forming shell.
9. In a renewable fuse-plug, a casing comprising, as a unitary structure, a ring of insulation material, an insulation-window disposed in the ring for closing the aperture thereof, and a body-member engaging-shell rigidly fixed at one end to the ring.
10. A fuse-plug shell comprising a ring of insulation material, an insulation-window seated in the ring, to close the aperture thereof, and a threaded metallic tube having one end fixed to the ring and permanently holding the window to its seat.
11. A renewable fuse-plug including, in combination, an externally threaded cup-shaped body-member, a replaceable fuse-strip having an intermediate portion disposed within the chamber of the body-member and an end-portion projecting exteriorly thereof, and a unitary casing removably threaded upon the body-member and comprising an insulation-ring and a threaded terminal-forming shell, the shell separably engaging electrically with the projecting end-portion of the strip.
12. A renewable fuse-plug including, in combination, an exteriorly threaded cup-shaped body-member, a replaceable fuse-strip having an intermediate portion disposed within the chamber of the body member and an end-portion projecting exteriorly thereof, and a unitary casing removably threaded upon the body-member and comprising an insulation-ring and a threaded terminal-forming shell separably engaging electrically with the projecting-end portion of the strip, the projecting end-portion of the strip being wedged between the shell and body-member in the threading of the casing upon the body-member.

In testimony whereof, I have signed my name to this specification.

WALTON D. WOOLLEY.
